UNITED STATES PATENT OFFICE.

EDWARD F. HOLZ, OF CHICAGO, ILLINOIS.

INK-FOUNTAIN FOR PRINTING-PRESSES.

1,077,882.

Specification of Letters Patent.

Patented Nov. 4, 1913.

Application filed April 21, 1913. Serial No. 762,683.

To all whom it may concern:

Be it known that I, EDWARD F. HOLZ, a citizen of the United States, residing at Chicago, in the county of Cook and State of Illinois, have invented certain new and useful Improvements in Ink-Fountains for Printing-Presses, of which the following is a specification.

The present invention relates to certain improvements in ink fountains for printing presses, and particularly rotary presses, although, as will presently appear, the invention is in no wise limited in its applicability to the above.

Many forms of printing presses are provided with ink fountains or troughs from which the ink is fed by means of a train or series of rollers until it is finally deposited on the printing form. The first or fountain roller of this train is adapted to take the ink from the fountain and transfer it to the next roller of the train. This fountain roller may operate either continuously or intermittently, and may be partially submerged in, or in contact with, the ink of the fountain at all times; or it may serve to withdraw the ink from a groove or slit of the fountain from time to time.

On account of the fact that the ink ordinarily used is of high viscosity, and hardens somewhat rapidly, particularly where it is exposed to the atmosphere, it has been found that the ink will not naturally feed evenly and constantly up to the first roller of the train or series. It is found that as the operations continue, the ink tends to hold back or away from the first roller, so that in time said roller will cease to withdraw the proper amount of ink at each operation of the press, with the result that in time the printing will become uneven and consequently unsatisfactory. In order to meet this difficulty it is generally necessary for the pressman to carefully watch the fountain to see that the ink is properly feeding at all points throughout its length, and it is necessary for him to uniformly press the ink up against the said first roller from time to time.

I am aware of the fact that heretofore certain attempts have been made to overcome the objections above outlined, but as far as I am aware, in the past such attempts have been wholly or partially unsuccessful. This has been true either for the reason that whatever device was adopted for automatically

forcing the ink up to the inking roller operated intermittently and not continuously, or else such device was built in and constructed as a permanent portion or structure of the fountain. Consequently the latter could not be easily and thoroughly cleared from time to time in order to keep the press in proper condition, and as must be done when it is desired to change the color or quality of the ink.

The main objects of the present invention are to provide mechanisms or devices for automatically feeding the ink up to the first roller of the series or train, such devices being operated continuously from a suitable moving part of the press or otherwise. With such an arrangement the stirring up of the ink in the fountain, and its advancement toward the first roller, will proceed uniformly, thereby greatly improving the ink feed, and at the same time keeping the ink itself in better condition.

Another object of the present invention is to so construct the aforementioned mechanism or device that it can be readily and easily removed from the fountain, thereby making it possible to more easily and thoroughly clean the fountain and associated parts, and supplying an incentive to the pressman to keep his press in better condition.

Other objects and uses will appear from a detailed description of the invention which consists in the features of construction and combinations of parts hereinafter described and claimed.

In the drawings: Figure 1 shows a plan view of an ink fountain and the first roller of a train, the fountain being provided with one form of device embodying the features of the present invention, and the middle portion of the mechanism being cut away; Fig. 2 is a cross section taken on the line 2-2 of Fig. 1 looking in the direction of the arrows; Fig. 3 is a detail section taken on the line 3-3 of Fig. 1 looking in the direction of the arrows; Fig. 4 is a plan view similar to that of Fig. 1 with the exception that the fountain therein illustrated is provided with a modified form of device of the present invention; Fig. 5 is a cross section taken on line 5-5 of Fig. 4 looking in the direction of the arrows; Fig. 6 is a detail longitudinal section of the shaft and paddles showing how the latter can be easily re-

moved by the withdrawal of a retaining pin; and Fig. 7 is a detail perspective of one of the paddles of Figs. 5 and 6.

In the several figures the ink fountain is designated by the numeral 8. It is generally in the form of an open top pan or tray, the bottom of which slants downwardly toward the first roller of the train. Ink fountains are of familiar constructions, and it is not deemed necessary in the present case to describe in detail the particular fountain illustrated.

In the particular construction illustrated the first roller of the train is designated by the numeral 9. As herein illustrated it occupies a position across one side of the fountain so that the ink 10 stands against the roller, whereby as the latter is rotated it will withdraw the desired amount of ink upon its periphery. The roller is adapted to rotate in the direction illustrated by the arrows in Figs. 2 and 5 so that the ink is withdrawn from the bottom portion of the fountain. In order to control the amount of ink thus withdrawn there is provided a flexible plate 10^a which extends along the fountain immediately beneath the roller and the position of which can be accurately adjusted by means of screws 11. These set screws serve to determine the amount of clearance between the plate and the roller. As the roller is rotated either intermittently or continuously it tends to pull the ink down toward the bottom of the fountain so that in time the area or contact between the ink and the roller will be reduced, and in fact may entirely cease in time. In order to overcome this difficulty I have provided means for constantly pressing or forcing the ink of the fountain up toward and against the roller, at all points throughout its length, thus removing the pressman of the necessity of watching the ink feed, and at the same time constantly stirring up or kneading the ink so that it will remain at all times of uniform consistency and quality throughout its mass. For the sake of convenience I shall hereinafter designate the aforementioned pressing or forcing means as a pressing or agitating device.

In the arrangement shown in Figs. 1, 2, and 3 the pressing or agitating device takes the form of a zig-zag bar 12 which extends across the length of the fountain and is so mounted that as it is rotated its projecting arms will be forced down into the ink, and then across the fountain to carry the ink toward the ink roller. Thus the bar serves the two functions of stirring up the ink and of carrying it over against the roller. This bar preferably rotates in the direction illustrated by the arrows in Fig. 2, that is, its projections travel toward the roller during the lower half of their rotation. When so rotated any given arm will enter the ink

approximately at the point 13, and, after sweeping through the ink and toward the roller, will emerge approximately at the point 14. From this it will be seen that a very effectual agitation and stirring up of the ink will ensue as well as an effectual transfer of the ink toward the roller. This zig-zag bar finds bearings at the two ends of the fountain, and is so mounted that it can be readily removed. For this purpose there is provided a short or stub shaft 15 which extends through the end wall 16 of the fountain, being held in place by means of a pair of collars 17 and 18 which have the set screws 19, and said stub shaft carries the pulley 20 by which it may be continuously driven from any suitable point. The inner end 21 of this stub shaft preferably terminates at a point close to the end wall 16, and it is provided with an angular socket or hole for the reception of the end 22 of the agitator bar. As shown in Fig. 3 this socket is squared in the particular arrangement illustrated, but of course any other form might be adopted, it being simply necessary that a driving connection shall be established between the stub shaft and the bar. Obviously the end 22 of the bar may be withdrawn from the stub shaft by allowing the bar to move away endwise therefrom. For this purpose I have provided a socket bearing at the other end of the fountain. Said bearing preferably takes the form of a threaded spindle 23 which is extended through the end wall 24 of the fountain, and is provided with the milled head 25 whereby it may be easily rotated. A set screw 26 may be provided for locking the spindle in position. This spindle is preferably provided with a bearing socket for the reception of the end 27 of the agitator bar so that the latter may easily rotate while held properly centered and in position.

It will be noted from examination of Fig. 1 that the end 27 of the zig-zag bar terminates at a point within the end wall 24. Therefore as soon as the spindle 23 has been threaded back flush with the end wall the end 27 of the bar can be raised up above the wall to permit the bar to be withdrawn endwise from the socket of the stub shaft 15. It is preferred that washers or the like 28 be interposed between the collar 17 and the end wall 16 for the purpose of effectually preventing the access of ink to the bearing within which the stub shaft 15 rotates.

The arrangement shown in Figs. 4, 5, 6, and 7 is similar to that just described in that in this case also the agitator is adapted to be rotated continuously, and in that it is so constructed that it can be readily removed, or at any rate removed to such an extent that it can be readily cleaned and so that the fountain can also be readily cleaned. In the present case a transversally extending shaft

29 finds bearings in the end walls 16 and 24, collars or the like 30 being provided for properly centering the shaft and preventing any end movement. This shaft is provided throughout its length with transversally extending slots or openings into which may be inserted a series of paddles or the like which, as shown in Fig. 5, will work down into the ink of the fountain to keep it properly stirred up, and to carry it over against the inking roll. In the particular arrangement illustrated, U-bars 31 are shown as being extended through the openings of the shaft, but it will be understood that other forms of paddle or bar might be substituted if desired.

For the purpose of holding all of the paddles in position on the shaft 29, I have provided a removable rod 32 which can be extended throughout the length of said shaft, passing through holes or openings 33 in each of the paddles, so as to prevent the said paddles from becoming displaced with respect to the shaft. This rod 32 is preferably provided with a milled head 34 and with a threaded end portion 35 which is adapted to thread into the end of the shaft 29 so that when it is desired to lock the paddles in position, the rod may be shoved in until the threaded portion 35 reaches the end of the shaft, whereupon the portion 35 may be threaded up to lock the rod in position. In the present case also a pulley 20 is provided whereby the agitator may be continuously rotated.

It will be noted from an examination of Figs. 1 and 4 that in each of the constructions therein disclosed the agitator and presser shaft is substantially in line with the upper portion of the roller. By so relating the parts the paddles of the agitator can be made to break through the surface of the ink contained in the fountain to effectually knead or mix the same and at the same time, by rotating the agitator in the direction previously mentioned the ink will be effectually carried over against the roller.

I wish to call particular attention to the fact that in each of the constructions herein illustrated I have provided means for continuously rotating the agitator as distinguished from means for providing an intermittent rotation. I am familiar with certain forms of construction in which an intermittent rotation is secured, but as previously pointed out such a rotation presents the serious disadvantage that it does not serve to carry the ink up against the roller uniformly, nor does it serve to keep the ink properly stirred up or kneaded as it were, to maintain it of uniform viscosity and quality throughout its mass. I wish also to call particular attention to the fact that in each of the herein described and illustrated constructions the agitator and presser is either removable in its entirety, or else it is removable to the

extent that the paddles or other projections which would seriously interfere with a cleansing operation are removable, so that in either case the ink fountain and the associated parts or elements can be readily cleaned notwithstanding the provision of the improvements of the present invention.

I claim:

1. In a device of the class described, the combination with an ink fountain and an inking roller adapted to receive ink from the same, of a rotatable device mounted within the fountain, a plurality of sidewise projecting extensions on the same adapted to agitate the ink within the fountain and to carry the same toward the inking roller, and means for rotating said member in a direction to carry said projections toward the inking roller when they are in the lower portion of their circular travel, substantially as described.

2. In a device of the class described, the combination with an ink fountain and an inking roller adapted to receive ink from the same, of a rotatable member having its axis of rotation substantially on a level with the upper portion of the inking roller, a plurality of sidewise projecting extensions on the said member adapted to break through the surface of the ink in the fountain when the member is rotated for the purpose of maintaining the ink in uniform condition throughout its mass, and means for continuously rotating said member in a direction to carry said projections toward the inking roller when they are in the lower portion of their circular travel for the purpose of continuously agitating the ink and carrying the same toward the inking roller, substantially as described.

3. In a device of the class described, the combination with an ink fountain and an inking roller adapted to receive ink from the same, of a stub shaft mounted in one wall of the fountain, a driving element mounted on the stub shaft, there being a driving socket on the inner end of the stub shaft, a socket bearing mounted in the opposite wall of the fountain and a rotatable device having one end mounted in the driving socket of the stub shaft and having its other end mounted in the socket bearing, said rotatable device having a plurality of sidewise projecting extensions adapted to carry ink contained in the fountain toward the inking roller, substantially as described.

4. In a device of the class described, the combination with an ink fountain and an inking roll adapted to receive the ink therefrom of a stub shaft carried by one wall of the fountain, a driving element mounted on the stub shaft, there being a driving socket on the inner end of the stub shaft, a threaded stud carried by the opposite wall of the fountain, and a rotatable device hav-

4
ing one end inserted in the socket of the stub shaft and the other end inserted in the socket of the stud, said rotatable device having a plurality of sidewise projecting extensions adapted to carry ink contained in the fountain toward the inking roller, substantially as described.

5. In a device of the class described, the combination with an ink fountain and an inking roller adapted to receive ink therefrom of a stub shaft carried by one wall of the fountain, a driving element mounted on the stub shaft, there being a driving socket on the inner end of the stub shaft,

a bearing carried by the opposite wall of 15 the fountain and mounted for adjustment toward and from the stub shaft, and a rotatable device having one end mounted in the socket of the stub shaft and the other end in the adjustable bearing, said rotatable 20 device having a plurality of sidewise projecting extensions adapted to carry ink contained in the fountain toward the inking roller, substantially as described.

EDWARD F. HOLZ.
